GREASE GUN AND FITTING

Filed May 17, 1941

UNITED STATES PATENT OFFICE

2,320,780

GREASE GUN AND FITTING

William T. Jennings, Medford, and Raymond F. Clark, North Billerica, Mass.

Application May 17, 1941, Serial No. 394,026

1 Claim. (Cl. 284—17)

This invention relates to a grease gun and a fitting therefor, and it is an object of the invention to provide a device of this kind of a portable character and one which can be employed with facility in forcing lubricating grease where desired.

It is also an object of the invention to provide a gun and fitting which when assembled for use is held in effective working position upon a bearing or kindred element with which the gun is to be used.

The invention consists in the details of construction and in the combination and arrangement of the several parts of my improved grease gun and fitting whereby certain important advantages are attained, as will be hereinafter more fully set forth.

In order that my invention may be the better understood, I will now proceed to describe the same with reference to the accompanying drawing, wherein—

Figure 1 is a view, partly in section and partly in elevation, illustrating a grease gun and fitting therefor constructed in accordance with an embodiment of my invention and shown in position for lubricating a locomotive rod;

Figure 2 is a detailed sectional view taken substantially on the line 2—2 of Figure 1;

Figure 3 is a view in top plan of the device as herein disclosed, the plunger arm being in fragment; and

Figure 4 is a view in bottom plan of the gun free of its fitting.

As disclosed in the accompanying drawing 1 denotes the barrel of the improved grease gun and one end portion of this barrel is tapered, as at 2, and having its outer or reduced end continued by an exteriorly threaded extension 3. This extension 3 is at the discharge extremity of the barrel 1 and the bore 4 of the barrel extends entirely therethrough and through the extension 3. The bore 4 at its end portion thereof remote from the extension 3 is of increased diameter providing at said end portion a stepped inner wall resulting in an internal annular shoulder 5 facing toward the outer end of the barrel 1. Snugly engaging within this outer enlarged portion of the bore 4 of the barrel 1 is an elongated plunger 6 which has its inserted end portion reduced in diameter so as to have effective engagement within the inner or reduced portion of the enlarged bore. This reduced part 7 of the plunger 6 is of a length substantially co-extensive in length with the length of the inner reduced part 8 of the enlarged bore.

The plunger 6 is of such a length as to extend beyond the outer end of the barrel 1 when the plunger 6 is at the limit of its movement inwardly of the barrel. The outer end portion of the barrel 5 is provided with the outstanding spaced and parallel plates 8 provided with the laterally extending ears 9 between which is pivoted, by a pin 10, an end portion of an elongated plunger arm 11. This plunger arm 11 is freely disposed through a slot 12 in the outer portion of the plunger 6. The part of the arm 11 working in the slot 12 is provided with the oppositely directed rounded lugs 14 for contact with the opposite end walls of the slot 12 whereby upon proper swinging movement of the arm 11 the plunger 6 may be retracted or forced inwardly of the barrel to shoot grease therefrom to the part to be lubricated.

The barrel 1 adjacent to the lower end of the enlarged portion of the bore 4 is provided with a laterally disposed and relatively large filling opening 15 continued through an outstanding boss 16. When the plunger 6 is retracted the grease may be placed within the bore 4 of the barrel 1 to be forced out through the extension 3 when the plunger 6 is moved under pressure inwardly of the barrel 1. It is to be noted that the opening 15 is a material distance above the inner extremity of the enlarged portion of the bore 4 so that as the plunger passes inwardly of the barrel 1 it will close the opening 15 and thereby assure the desired forcing of the grease out through the extension 3.

The extension 3 threads into the central portion of an attaching member or plate 17, and this plate 17 in its outer face is provided substantially radially thereof with a slot 18 opening through the periphery of the member 17. The side and closed end walls of this slot 18 are undercut or grooved, as at 19, whereby the plate 17 may be readily slid upon and interlocked with a fitting 20. The outer extremity of the extension 3 of the barrel 1 has its periphery smooth, and brazed to this outer extremity is a surrounding washer 21 fitting within a suitable pocket 22 provided in the under face of the member 17. This washer 21 provides means whereby the barrel 1 and member 17 are effectively held in assembled relation. The fitting 20 has an end portion 23 rounded and exteriorly threaded so that it can be threaded within a lubricating opening 24 of a part to be lubricated. This fitting 20 can be readily removed or applied as desired.

The bore 25 of the fitting 20 has its outer end

reduced to provide an entrance opening 27 registering with the outer end of the bore 4 through the extension 3 of the barrel 1. This reduced portion of the bore 25 provides an inwardly facing valve seat 28 with which coacts a ball valve 29 loosely placed within the inner portion of the bore 25. This ball valve 29 has sufficient movement lengthwise of the bore 25 to allow lubricant to be forced out to the work, but will seat against the valve 28 under the action of any lubricant seeking to escape out through the fitting 20.

The extent of movement of the ball valve 29 away from its seat 28 is limited by a tubular plug 30 threading into the bore 25 of the fitting 20 and into the end portion of the bore 25 remote from the valve seat 28. This plug 30 has its wall provided at the inserted end thereof with a desired number of notches or recesses 31, each of a size to allow grease to be forced out through the plug 30 without hindrance by the valve 29 when at the limit of its movement as determined by the plug 30.

The fitting 20 intermediate its ends is provided with an outstanding surrounding flange 26 to provide means to limit the extent of the insertion of the portion 23 of the fitting 20 into the lubricating opening 24 and also to provide a head to be gripped by a suitable tool to facilitate application or removal of the fitting 20.

In view of the foregoing it is believed to be apparent that my improved grease gun and fitting may be readily applied and when in applied position the grease may be readily forced to the part desired to be lubricated.

From the foregoing description it is thought to be obvious that a grease gun and fitting constructed in accordance with my invention is particularly well adapted for use by reason of the convenience and facility with which it may be assembled and operated.

I claim:

In combination with the discharge end portion of the cylinder of a grease gun, a substantially flat attaching plate surrounding the discharge extremity of the barrel, means for rigidly securing said plate to the discharge extremity of the barrel, a tubular fitting to be operatively placed with respect to a lubricating opening, the outer face of the plate being provided substantially radially thereof with a slot open at one end through the periphery of the plate, a part of the fitting being slidable into the slot, said part and the side walls of the slot interlocking, the bore of the barrel and fitting being in register when the barrel and fitting are engaged, the bore of the fitting having an internal valve seat, a ball valve within the member and coacting with said valve seat to prevent retrograde flow through the fitting, and a tubular plug within the end portion of the bore of the fitting remote from the valve seat to limit the movement of the ball valve away from the seat, the inserted end of the plug having its wall provided with notches to allow grease to be forced out through the plug without hindrance by the ball valve when said valve is at the limit of its movement as determined by the plug.
